UNITED STATES PATENT OFFICE

106,169

DESIGN FOR A DISH OR SIMILAR ARTICLE

Adolph Jungwirth, Praha, Czechoslovakia

Application July 15, 1937, Serial No. 70,460

Term of patent 3½ years

To all whom it may concern:

Be it known that I, Adolph Jungwirth, a citizen of Czechoslovakia and a resident of Praha, Czechoslovakia, have invented a new, original, and ornamental Design for a Dish or Similar Article, of which the following is a specification, reference being had to the accompanying drawing, forming part thereof.

The dominant feature of the design resides in the winged handles of the dish and of the handle of the cover.

Fig. 1 shows a plan view of a dish or similar article showing my new design; and

Fig. 2 shows a front elevational view of the same.

I claim:

The ornamental design for a dish or similar article, substantially as shown and described.

ADOLPH JUNGWIRTH,
